STANCHION

Albert H. Magness, Bel Air, Md.

Application November 7, 1947, Serial No. 784,695

3 Claims. (Cl. 119—150)

1

This invention relates to improvements in cattle stanchions and has specific reference to an improved locking mechanism which joins the separable parts thereof.

Cattle stanchions normally are provided with locking mechanisms adapted to secure the movable bar of the stanchion in closed relationship with the stationary bar. It has been found that these bar locks tend to snap open when cattle throw their heads back or suddenly pull away from the stanchion. Furthermore, the locking mechanisms are subjected to hard usage and tend to wear out rapidly. The working parts, particularly springs, become dislocated, or bent, or jarred out of alignment under the severe treatment they receive.

Accordingly, a primary object of the present invention is to provide a positive locking mechanism for use with cattle stanchions, wherein the locking parts are completely enclosed when in locked position, and thus secured against damage or accidental displacement.

Another object of the present invention is to provide an improved latch device for a stanchion locking mechanism which is simply and inexpensively constructed, and which may be operated easily by the attendant.

A further object of this invention is to provide a novel stanchion latch and mounting therefor, including improved means for movably connecting a movable stanchion bar with the relatively fixed portions of a stanchion whereby the movable bar may be positively secured, easily released, and its movement limited upon release.

Still a further object of this invention is to provide a simple and sturdy stanchion lock assembly, characterized by marked utility and efficiency in operation, yet which is inoperable by any form of pressure exerted by cattle.

Other objects and advantages of the present invention will be apparent from the following detailed description thereof and the drawings, wherein:

Figure 1 is a perspective view showing a cattle stanchion embodying the present invention, with the dotted lines showing the movable stanchion bar in opened position;

Figure 2 is a vertical section of the lock mechanism of the invention including the supporting brackets therefor;

Figure 3 is a horizontal sectional view of the locking mechanism taken along the line 3—3 of Figure 2;

Figure 4 is a transverse vertical section taken along the line 4—4 of Figure 2; and

2

Figure 5 is a horizontal section of the locking mechanism taken along the line 5—5 of Figure 2.

Referring to the drawings, a conventional type of cattle stanchion is shown in Figure 1, the stanchion being positioned on a suitable flooring 10. The stanchion is shown as suspended from a stall frame 11 comprising bars 12 and securing brackets 13, by a support chain 14 and an anchor chain 15. The stanchion itself comprises a relatively stationary bar 16 which is provided with elbow extensions 17 and 18. A relatively movable bar 19 is pivoted at 20 on the elbow extension 18, for movement between a closed and an open position, the latter being shown by the dotted lines in Figure 1.

In accordance with the present invention, the stanchion shown is provided with a novel locking device for securing the movable bar 19 in a desired position, which includes means for enclosing all of the working parts of the lock against damage or accidental operation, and secures the bar 19 positively in the absence of cumbersome or exposed auxiliary locking mechanism.

The locking device includes a sleeve 21, suitably secured to the tubular extension 17 as by bolts 22 and provided with flanges 23 which are attached to a suspending bracket 24 on the chain 14 by a bolt 25. As shown in Figures 2 and 4, the sleeve 21 is provided with a laterally extending member 26 having vertical walls 27 and a vertically depending back plate 28. These members cooperate to form a lock housing indicated generally by the numeral 29 open at its outer end and adapted to receive a locking mechanism indicated at 30, secured to the free end of the movable bar 19. The plate 28 is apertured centrally at 31, to permit passage of a latch connecting mechanism therethrough. The sleeve 21 is provided with a depending flange 32 which serves as a stop member or guide for locating the locking mechanism 30 positively in home position. The vertical walls 27 of the housing 29 are provided with lugs 33 positioned in opposed relationship on the inner walls thereof, for purposes to be described.

The locking mechanism 30 on the movable bar 19 includes a sleeve 34 formed with flanges 35 adapted to be drawn together on the movable bar 19 by a bolt 36 or other suitable means to secure the sleeve 34. The sleeve 34 supports a latch housing 37 formed integrally therewith and having a top plate 38, a base plate 39, and an end plate 40.

The plate 40 is provided with a flange 41 extending perpendicularly therefrom in alignment 55 with the aperture 31 in the plate 28. The flange

41 serves as an anchor plate for connection with a connecting rod 42 secured thereto by a pivot 43. It will be noted that the ends of the pivot 43 are so formed as to abut the edges of the aperture 31 when the latch mechanism 30 is in the home position shown in Figure 2, thus securing the locking device firmly against misplacement. The rod 42 is formed at its other extremity with a depending member 44 which engages with the plate 28 and thus serves to limit outward movement of the movable bar 19 when the stanchion is opened.

The latch housing 37 receives a latching assembly indicated at 45 including two latch levers 46 and 47 pivotally mounted at their inner ends to a pivot member 48 secured by a nut 49 to the latch housing 37. The levers 46 and 47 are provided with identical handles 49 for manipulation between a normal latching position as shown in Figure 3, and an unlatched position, attained by inward compression of the handles 49 against the action of a spring 50 mounted on the pivot member 48. The spring 50 is provided with end portions 51 which engage with side walls 52 of the said levers to maintain the levers firmly in a normal latching position, under spring tension.

As shown best in Figure 2, the levers 46 and 47 are provided with slots 53 which engage with the lugs 33 on the inner walls of the latch housing 37 to secure the levers 46 and 47 in latched position, when the movable bar 19 is moved to closed position as shown in Figure 1.

The levers 46 and 47 are further provided with opposed plates 54 having arcuate grooves 55 adapted to receive a guide post 56 secured to the latch housing 37. The grooves 55 and post 56 serve to guide arcuate movement of the levers upon compression of the handles 49 and further to limit lateral expansion of the levers under the tension of the spring 50 when the latching mechanism is unlocked and withdrawn from the locking housing 29. Thus it will be seen that the lever handles 49 always form a fork or a U shaped member, whether the mechanism is in locked or unlocked position.

As shown in the drawings, stanchions of this type conventionally are suspended by the strap or chain 14 at the top and anchored by the chain 15 at the bottom. The chains are arranged so as to give freedom of movement to an animal secured in the stanchion. When not in use, the stanchion is usually left in the open position shown in Figure 1. In this case, the movable bar 19 may be positioned against the adjacent stall post 12 of the stall frame and is prevented from falling to the floor by means of the fork-forming latch levers 46 and 47. However, even when the stanchion is open, the movable bar is at no time freed from connection with the stationary bar 16, for the rod 42 serves to maintain connection between the two bars at all times, preventing the movable bar 19 from falling to the ground if the fork formed by the handles fails to engage with the adjacent stall post 12. Similarly, the rod 42 guides the movable bar 19 and its latching member 30 to closed position when the stanchion is closed.

In operation, in order to swing the movable bar 19 to open position, one grasps and compresses the extending handles 49 of the latch levers 46 and 47 until they contract sufficiently to free the apertures 53 from the lugs 33. The bar 19 and latch mechanism 30 are then swung free of the lock housing 29. It will be noted that an animal cannot disengage the mechanism by pressing against a particular latch handle, for should one

latch handle be compressed from its locking position, the other will remain in engagement with its adjacent lug, locking the mechanism against disengagement. Both handles 49 must be compressed in order to free the mechanism.

To close the stanchion, the operator may push the movable bar 19 inwardly and the bar 19 will be guided automatically to home position by the rod 42, whereupon the latch mechanism 30 is again secured by the lugs 33 on the lock housing 29. As the movable bar 19 is moved towards closed position, the wedge-shaped latch mechanism is compressed until the slots 53 are opposite the lugs 33. The latch mechanism then expands under the spring action to secure the movable bar in closed position.

It is to be noted that the present invention provides a stanchion lock characterized by a minimum of projecting rods, bolts and similar elements which are liable to injure an animal, or are liable to become broken and bent and render the stanchion inoperative. The stanchion lock parts are completely protected from accidental operation, and are of simple and sturdy construction. The locking mechanism is inexpensive to construct, and easy to install.

The specific embodiment of the invention disclosed is intended to include all obvious modifications, use of mechanical equivalents or changes in construction, shape, arrangement and combination of parts, which may come within the scope of this invention, as set forth in the appended claims.

I claim:

1. In a stanchion including a fixed upright bar having coplanar upper and lower elbow extensions, a movable bar having one end pivotally attached to the free end of said lower extension with its free end swingable from an open to closed position relative to the free end of the upper extension, and extensible rod means connecting the free end of said movable bar with said upper extension and serving to guide said free end in alignment with the upper extension, the improvement comprising a pivot pin secured to the free end of said movable bar and coaxially aligned therewith, a pair of levers each having an end pivotally connected to said pin, spring means resiliently urging the said levers apart, a socket member secured to the free end of said upper extremity and extending axially therefrom and adapted to receive said levers in said closed position, said socket member having an open free end and side walls diverging from the extension to said open end, and cooperative latch elements extending respectively from the inner surface of each wall and the outer surface of each lever and interengageable when said levers are received in said socket to latch said movable bar in said closed position.

2. In a stanchion including a fixed upright bar having coplanar upper and lower elbow extensions, a movable bar having one end pivotally attached to the free end of said lower extension with its free end swingable from an open to closed position relative to the free end of the upper extension, and extensible rod means connecting the free end of said movable bar with said upper extension and serving to guide said free end in alignment with the upper extension, the improvement comprising a latch housing secured to the upper end of said movable bar and having a semi-cylindrical end wall coaxially aligned therewith, a pivot pin carried within said housing coaxial with said wall, a pair of levers each having an end

pivottally connected to said pin, spring means resiliently urging the said levers apart, a socket member secured to the free end of said upper extremity and extending axially therefrom and adapted to receive said levers in said closed position, said socket member having an open free end and side walls diverging from the extension to said open end, and cooperative latch elements extending respectively from the inner surface of each wall and the outer surface of each lever and interengageable when said levers are received in said socket to latch said movable bar in said closed position.

3. In a stanchion including a fixed upright bar having coplanar upper and lower elbow extensions, a movable bar having one end pivotally attached to the free end of said lower extension with its free end swingable from an open to closed position relative to the free end of the upper extension, and extensible rod means connecting the free end of said movable bar with said upper extension and serving to guide said free end in alignment with the upper extension, the improvement comprising a latch housing secured to the upper end of said movable bar and having a semi-cylindrical end wall coaxially aligned therewith, spaced parallel upper and lower walls extending perpendicularly to the axis of said movable bar, a pivot pin extending between said upper and lower wall coaxial with said end wall, a pair of levers each having an end pivotally connected to said pin and free
